UNITED STATES PATENT OFFICE.

MAXIMILIAN GRAFF, OF BRANDENBURG, GERMANY.

MARGIN-SETTING DEVICE FOR TYPEWRITERS.

1,413,721.

Specification of Letters Patent. Patented Apr. 25, 1922.

Application filed September 14, 1920. Serial No. 410,320.

To all whom it may concern:

Be it known that I, MAXIMILIAN GRAFF, German citizen, residing at Brandenburg, Germany, have invented certain new and useful Improvements in Margin-Setting Devices for Typewriters, of which the following is a specification.

The invention relates to a device on typewriters by means of which the stops arranged behind the platen carriage and operating to determine the width of the margins can be conveniently set by a lateral crank handle. An important feature of the invention consists in a stop member being arranged to be shifted on each of a number of spindles when the latter are turned by their respective handles, a rotating scale being associated with each crank handle and indicating the position of the stops at the front of the machine.

In typewriters whose mechanism is arranged so as to leave a clear space at the front, in order to provide for visible writing and for a free access to the ink ribbons, the stops for setting the margins are placed behind the platen carriage. This arrangement of the stops, which are adapted to be set by keys or handles, is inconvenient, because the typist has to rise from his seat before he is able to reach the said parts for shifting the stops. This involves a great loss of time.

In typewriters that have the said stops arranged in front of the platen carriage, the margins can be readily set, but the view of the writing sheet is obscured and the parts located at the front make the ink ribbons difficult of access.

By the present invention these drawbacks are removed and the setting of the margin can be performed instantly, this advantage being particularly noticeable in writing on forms and accounts of different sizes.

A constructional form of the invention is shown in the drawing in which—

Fig. 1 illustrates a side view of a stop and a crank handle drive with a drum-shaped scale arranged on a side cheek of the machine which is shown in section.

Fig. 2 is a horizontal section of the crank drive on the line A—B of Fig. 1.

Fig. 3 represents the surface of the scale-bearing drum rolled out flat.

Figs. 4, 5, 6 and 7 are views of the part of the scale as seen from the front of the machine.

Fig. 8 shows the platen scale and the

drum scales as viewed from the front of the typewriter.

Fig. 9 represents a top view of the screw spindles with the margin stops. 60

Fig. 10 is a side view of the drum-advancing wheel.

At the rear wall of the typewriter 1 are bearing supports 2 in which screw spindles 3 and 4, Fig. 9, are revolvably mounted. 65

The screw spindles 3 and 4 operate to shift the stops 5 and 6 which have extensions 7 that are guided in a slot 8 in the rear wall of the machine. Each of the stops 5 and 6

has an upwardly extending tongue 9 against 70 which the striking surface 11 of the carriage

strikes as indicated in Fig. 1 so as to stop any further motion of the carriage. Fixed

on each of the screw spindles 3 and 4 is a sprocket wheel 12 which meshes with a chain 75

13 that transmits motion from a sprocket wheel 14 and a handle 15, Fig. 2. The

sprocket wheel 14 is fixed upon a shaft 16 whose one end is journalled in the side cheek

17 of the machine and whose other end is 80 journalled in a bearing arm 18. Mounted

on one end of the shaft 16 is a toothed wheel 21 that is in mesh with the toothed wheel

19 that is on the shaft of the scale-bearing drum. Fixed on the other end of the shaft 85

16 is a crank handle 15 which is provided with a protuberance 22 that is pressed by a

spring 23 into radial grooves 24 of the arresting ring 25. The movable scale consists

of a drum 20 provided with divisions and a 90

disk 27 with numerals. The drum 20 is fixed on the shaft 28 whilst the numeral disk 29 turns loosely on the same between

the drum and the transmission wheel 29 that

revolves with the shaft. The motion of the 95

transmission wheel 29 is transmitted to the

numeral disk 27 through an advancing wheel

30. The advancing wheel 30 turns loosely

on the shaft 31. The shafts 28 and 31 are

both journalled in the arms 18 and 32. The 100

numeral disk is advanced figure by figure

in a similar manner to an electricity meter

or a Veeder counter by the advancing wheel

30 being advanced to the extent of a single

tooth at each revolution of the advancing

wheel 29 by means of an isolated tooth 33

thereon (Fig. 10). The arrangement of the

rotating scale is such that only one horizontal row on the drum 20 and the numeral

disk 27 is visible at a time through the window 35 in the front 34 of the machine, so

that the breadth of the margin as measured

by the scale 36 will be indicated in the said window.

The mode of operation is as follows:

Assuming that a writing sheet is put onto 5 the platen 37 and slipped under the scale 36, and that the margin between the edge of the paper (which is located at, say, the numeral 5 on the scale) and the writing is to 10 extend up to the division 15 on the scale 36, then the handle 15 is turned until the numeral 10 and 5 divisions appear behind the window 35. By the protuberance or 15 detent 22 on the handle 15 entering into the slots 24 of the arresting ring 25 the particular stop is retained in the position indicated. The right hand platen carriage stop 6 is actuated in the same way.

I claim:

- 20 1. In a typewriter, a laterally movable platen carriage, a stop at the rear of the carriage for limiting the lateral motion of the same, a screw spindle for shifting the stop, a rotary scale at the front of the typewriter for indicating the positions of the stop, and a handle at the side of the typewriter for turning the scale and the said spindle.
- 25 2. In a typewriter, a laterally movable

platen carriage, a stop at the rear of the carriage for limiting the lateral motion thereof, a screw spindle for shifting the stop, a 30 rotary drum with scale divisions on its periphery, a rotary disk beside the drum, numerals on the disk, a handle at the side of the typewriter for indicating the positions of the stop, and means for transmitting the 35 motion of the handle to the spindle, the drum and the said disk.

3. In a typewriter, a laterally movable platen carriage, a stop at the rear of the carriage for limiting the lateral motion thereof, 40 a screw spindle for shifting the stop, a rotary drum with scale divisions on its periphery, a rotary disk beside the drum, numerals on the disk, a handle at the side of the typewriter for indicating the positions of the 45 stop, means for transmitting the motion of the handle to the spindle, the drum and the said disk, and a window at the front of the typewriter for disclosing only the portion of the drum that indicates the position of the 50 stop.

In testimony whereof I affix my signature.

MAXIMILIAN GRAFF.
